UNITED STATES PATENT OFFICE.

WILLIAM MORISON, OF MONTCLAIR, NEW JERSEY.

DESIGN FOR A BATTERY-CASE.

SPECIFICATION forming part of Design No. 23,916, dated December 25, 1894.

Application filed May 25, 1894. Serial No. 512,493. Term of patent 14 years.

To all whom it may concern:

Be it known that I, WILLIAM MORISON, a subject of the Queen of Great Britain, and a resident of Montclair, county of Essex, and 5 State of New Jersey, have invented a certain new and original Design for a Battery-Case, of which the following is a specification.

The leading feature of my design consists of a rectangular box, provided upon its front 10 face with a raised circular projection as is clearly shown in the drawings accompanying and forming a part of this specification, in which—

Figure 1 represents a perspective view of 15 my design, and Fig. 2 is a sectional view.

The front face of my battery case A, is approximately square in contour, and is of a depth of about half its height. Each side of the same is paneled substantially as represented at A², in the drawings, which panels fall 20 within and harmonize with the outer contour line of the said side. Within a circular lateral projection A⁴ of the front face is the figure B, the body of which is made parabolic

in contour and glass A⁶, circular in outline 25 and located within the contour of the said lateral projection A⁴.

The bottom of my battery case is provided with feet A³, and from the top of the same rise ornamental posts A⁵, and A⁷. 30

At the lower portion of one of the rectangular sides of my battery case is a projection A⁸.

The various parts of my battery case are harmonious and are well proportioned and the configuration of the same forms an ornamental and pleasing as well as a new and original 35 design.

What I claim is—

The design for a battery case herein shown and described.

In testimony of the foregoing specification I do hereby sign the same, in the city of New York, county and State of New York, this 17th day of May, A. D. 1894.

WILLIAM MORISON.
